UNITED STATES PATENT OFFICE.

RALPH ALPIN, OF TARRYTOWN, NEW YORK.

CLOTHES-LINE PULLEY.

No. 845,388.

Specification of Letters Patent.

Patented Feb. 26, 1907.

Application filed March 17, 1904. Serial No. 198,598.

To all whom it may concern:

Be it known that I, RALPH ALPIN, a citizen of the United States, and a resident of Tarrytown, in the county of Westchester and State of New York, have invented a certain new and useful Clothes-Line Pulley, of which the following is a specification.

This invention relates to the suspension of clothes-lines, and has for its objects a pulley that will admit of the entire length of a pulley-line to be utilized to hang clothes upon, that will allow the clothes-pins to pass over it easily, that will not entangle the garments on the line, and that for packing and transportation to the retail dealers will admit of being shipped in "knockdown" shape. These objects are attained by the means set forth in these specifications and the accompanying drawings.

Figure 1 is an elevation in cross-section of one of the pulleys. Fig. 2 is a plan of the same through line *e*. Fig. 3 illustrates the pulley suspended from a bracket with a line upon the pulley. Fig. 4 represents the fastening means for securing the ends of the wire arms to the plates. Figs. 5 and 6 illustrate a bracket-clamp. Fig. 7 shows a form of pin holding the pulley.

The pulley comprises two plates 1 2, Figs. 1, 2, united by wire arms 3. The two plates are substantially alike in construction, and one of them is shown in plan in Fig. 2 and both in cross-section in Fig. 1, the latter also disclosing the method of securing the wire arms to the plates. Five arms are shown; but more or less may be employed. These arms are made of wire, the upper terminal being adapted for hooking in the top plate, as in Fig. 1, the upper portion forming a loop projecting upward at an obtuse angle with the top plate, the middle portion curving under the top plate, then down and out, forming a loop at its lower portion, the outer wire of the loop resting in a notch in the bottom plate, the terminal of the wire forming the loop adapted to be secured in the plate. The plates have projections *i*, Fig. 2, that are notched at the ends to receive the wire arms, as at *n'*, Figs. 2 and 4, and are provided with holes *n'*, Fig. 4, through which pass the ends of the wire arms that are to be bent down upon the plate. The complete form of the wire arm is shown at the left in Fig. 1, showing how the ends *n n* of the wire arms are bent over upon the plates with some pressure after being passed through the holes in

the plates, as at 16 17, the bending securely fastening the wire arms to the plates. The ends *i* of the plates are supplied with lugs *l l* on one or both sides, but on one side will be sufficient, which form a channel *h* to receive one part of the wire arms that is bent upon the plate, thus preventing any side movement of the wire arms. For transporting these pulleys in bulk the ends of the wire arms are left straight, and the plates and arms are shipped disconnected, to be assembled by the purchasers, since it is only necessary to unite the wire arms with the plates and bend the ends of the wire to their places, as shown.

Between the loops at the lower ends of the arms a ring 5 is inserted. It is made of a size to make contact with the outer portions of the loops and requires no other fastening, as it cannot be displaced. Its object is to prevent the entanglement with the arms of articles hung on the line.

The pulley *a* is suspended from a bracket *b* by means of a pivotal pin 4, Figs. 3 and 7. Any kind of a bracket may be used, the pulley being given an inclination from the perpendicular, as in Fig. 3; but for the purposes of convenient and compact packing for transportation and for ease of adjustment for any surface a bracket is shown in Fig. 3. It consists of rods 9 10, having eyes on one end to receive the pin 4 and with means at their other ends for fastening to a wall or other support, as at 11 12. The two rods are constructed in such a manner that when their parts to be joined are brought together and are secured within a clamp 8 (shown in enlarged detail in Figs. 5, 6) the eyes upon the ends of the rods will be held in the proper position for their respective purposes. Fig. 5 shows the inside of one of the halves of the clamp, showing the grooves 14 15 made to receive the rods 10 9. In Fig. 6 an end view of the closed clamp is shown. This construction admits of the bracket being taken apart for transportation. The ends of the rods for fastening to a support may be bent to adapt the bracket to an uneven surface or to giving the pulley any cant that may be desired from the perpendicular.

In the forming of the arms 3 a short turn is made at the point 3', Figs. 1 and 3, to overcome a tendency of the line *e* to climb on the pulley when it is loaded with garments. If the line does creep up that high, it drops off readily and falls back to its natural groove,

which is shown by the position of the line *c* in Fig. 3.

Having described my invention, what I claim, and desire to secure by Letters Patent, 5 is—

1. A clothes-line pulley comprising a top plate and a bottom plate, the plates having central holes for suspension on a shaft, wire arms vertically secured to extensions on said plates, the tops of the arms extending above and outwardly from the top plate, curving inwardly and then out and downward below the bottom plate and back to the bottom plate, and a ring inclosed within the loops in 15 the bottoms of the arms, as set forth.

2. A clothes-line pulley comprising a top plate and a bottom plate, wire arms vertically secured to extensions of said plates, the tops of the arms extending above and outwardly 20 from the top plate, then curving inwardly

and downward, and thence out and downward below the bottom plate, thence backward and up to the bottom plate, a ring within the loop formed at the lower ends of the arms, a suspending-shaft through the 25 centers of said plates, and a bracket for holding the shaft comprising a pair of arms having eyes at one end for encircling the said shaft, the other ends of the arms attachable to a support, one of the arms being bent 30 and the other straight to fit a clamp, and a clamp to bind the arms in a manner to cant the pulley.

Signed at Tarrytown, in the county of Westchester and State of New York, this 23d 35 day of February, A. D. 1904.

RALPH ALPIN.
